UNITED STATES PATENT OFFICE.

CHARLES W. LUMMIS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,178,086.

Specification of Letters Patent.

Patented Apr. 4, 1916.

Application filed May 12, 1914. Serial No. 838,146.

To all whom it may concern:

Be it known that I, CHARLES W. LUMMIS, a citizen of the United States, residing at Worcester, in the county of Worcester and 5 Commonwealth of Massachusetts, have invented a new and useful Improvement in Gas-Producers, of which the following, together with the accompanying drawings, is a specification.

10 My invention relates to gas producers and more particularly to mechanism for supplying fuel to the producer.

One object of the invention is to provide an improved form of mechanism for automatically feeding fuel to a producer, the mechanism being adjustable to vary the rate at which the fuel is fed in accordance with the rate of consumption of fuel within the producer.

20 Another object of the invention is to provide means for spreading the fuel evenly, agitating its surface and breaking up masses thereof after it is received in the producer, the spreading means being arranged to rise 25 automatically with the surface of the fuel as the thickness of the fuel bed is gradually increased during the operation of the producer.

Another object of the invention is to provide means for causing the fuel to be deposited over a considerable area within the producer, this means being adjustable to vary its effect in spreading the fuel.

Further objects and advantages will appear from the following description taken 35 in connection with the accompanying drawings, in which—

Figure 1 is a side view of a gas producer equipped with fuel feeding and distributing means in accordance with my invention; Fig. 2 is a sectional elevation of a portion 40 of the fuel feeding and distributing mechanism shown in Fig. 1; Fig. 3 is a sectional plan view on the line 3—3 of Fig. 1; Fig. 4 is a sectional elevation on the line 4—4 of Fig. 2; Fig. 5 is a detail elevation of the 45 means for operating the fuel feeding and distributing mechanism; and Fig. 6 is a sectional elevation on the line 6—6 of Fig. 4.

50 Like reference characters refer to similar parts in the different figures.

In the form of the invention shown in the drawings the gas producer includes a lower stationary section 1, an upper stationary section 2 supported by the posts 3 and a central

or intermediate section 4. The central section 4 is rotatably supported by the rollers 5 and may be rotated in the direction of the arrows A by a shaft 6 carrying a pinion 7 which drives a rack 8 secured to the section 60 4. The joint between the stationary section 2 and the rotatable section 4 is sealed by a water seal 9 so as to prevent the escape of gases. The top of the upper section 2 is adapted to support a body of water 10 to 65 prevent overheating.

The fuel 11 which is to be fed to the producer passes through a hopper 12, the upper end of which, if desired, may communicate with a storage bin so that the hopper will 70 be charged by gravity. Below the hopper 12 is a shelf 13 upon which rests a ram 14, the ram sliding upon the shelf through an opening 15 in one side of the hopper. When the ram 14 moves outwardly through the opening 15 so as to uncover more or less of the shelf 13, a quantity of fuel drops upon the uncovered portion of the shelf, as shown in Fig. 2, so that when the ram moves back over the shelf some of the fuel is pushed 80 ahead of it through the opening 16 and beyond the opposite edge of the shelf, as shown in Fig. 4. As the fuel drops from the shelf 13 it is received in a secondary hopper 17.

Under the discharge opening of the secondary hopper 17 is a member 18 provided with a vertical pocket 19 and fitting slidably between a shelf 20 and the discharge opening of the hopper 17. The member 18 is reciprocated horizontally by a connecting 85 rod 21 driven by a crank 22, ratchet 23, pawl 24, lever 25, connecting rod 26 and lever 27. The lever 27 is caused to raise the connecting rod 26 by the pins 28, carried on the rotating section 4, striking against the lever 29, the weight of the parts causing the lever 29 to return to its initial position against the support 30 after each pin has passed it. The ram 14 is actuated by a bracket 31 carried by the pocket member 18, the upper end of the bracket sliding loosely on a rod 32 projecting from the ram, the rod 32 carrying an adjustable stop 33. The travel of the ram 14 may be varied in extent by adjusting the position of the stop 33 so as to vary the quantity of fuel fed into the hopper 17 during each cycle of movement of the ram. The pins 28 are removable and, by increasing or decreasing the number of these pins, the number of feeding movements of the ram 110

14 and, therefore, the quantity of fuel supplied to the producer during each revolution of the section 4 of the producer may be varied to regulate properly the supply of fuel in accordance with its consumption.

A conduit or chute 34 incloses a passageway 35 connecting an opening through the shelf 20 with the combustion chamber of the producer. This passageway 35 is out of vertical alinement with the discharge opening of the secondary hopper 17 so that the shelf 20 closes the bottom of the pocket 19 when the member 18 is in position to receive fuel from the hopper 17, as shown in Fig. 4. The movement of the pocket member 18 carries the pocket 19 back and forth between the discharge opening of the hopper 17 and the upper end of the passageway 35, so that the fuel received from the hopper 17 is pushed along the shelf 20 until it drops through the passageway 35 into the combustion chamber and onto the bed of fuel contained therein. The pocket member 18 is provided with an extension or shelf 36 adapted to close the discharge opening of the secondary hopper 17 while the pocket 19 is carrying fuel to the passageway 35 and returning. The least horizontal distance between the discharge opening of the hopper 17 and the upper end of the passageway 35 is slightly greater than the greatest horizontal length of the pocket 19, so that communication between the hopper 17 and the passageway 35 can never be established through the pocket. It is obvious that any fuel pushed off the shelf 13 by the ram 14 before the pocket 19 returns beneath the hopper 17 will rest temporarily upon the extension or shelf 36, but will be pushed into the pocket 19 by the lower edge of the hopper 17 as the pocket 19 is returned for more fuel. An extension 36a prevents escape of gas through the chute 34 while the pocket 19 is receiving fuel.

The wall of the chute 34 nearest the hopper 17 is provided with a series of vanes or plates 37 which diverge downwardly so as to scatter or distribute the fuel over the surface of the fuel bed within the producer as the fuel drops by gravity through the spaces between these vanes. A second series of vanes or plates 38 are secured to the wall referred to by means of nuts 39 so as to be angularly adjustable, the angular adjustment of these latter vanes serving to increase or decrease their effect in spreading the fuel. The wall of the chute 34 which carries the vanes 37 and 38 is preferably inclined somewhat so that the fuel will not be so liable to be pushed into the open space beyond the vanes but will be more certain to slide down the wall through the spaces between the vanes.

In order that the fuel may be supplied more evenly upon the surface of the bed of

fuel within the producer, a horizontal fuel spreader 40 is provided to thoroughly distribute the fuel which is dropped through the passageway 35, as the said fuel is rotated by the movement of the intermediate section 4 of the producer. The spreader 40 is preferably located just in front of the point at which the fuel is deposited so that the fuel is spread out and distributed before it has a chance to become fused together or otherwise unduly obstruct the gases rising through the fuel. The fuel spreader 40 is also located in a line which is offset from the axis of rotation of the section 4 of the producer so that the path of the fuel as it reaches the spreader is oblique to the line of the spreader. The chute 34 is located so as to deposit the fuel near the side wall of the producer, the fuel being thus moved toward the outer end of the spreader 40. It is obvious that the peculiar position of the spreader will tend to sweep the fuel toward the center of the producer so as to distribute it uniformly. The spreader 40 is hollow and is carried by a pair of pipes 41 extending through the top of the producer and a flexible tube 42 is connected with each of the pipes 41 so that the spreader and pipes may be water cooled.

A cross bar 43 between the two pipes 41 is engaged by the forked extremity of a lever 44 supported on a pivot 45, this lever thus serving to support the spreader and pipes and to determine the vertical position of the spreader with reference to the surface of the fuel bed. The opposite end of the lever 44 is forked and engages a nut 44a threaded onto a screw 46, which rotates in fixed bearings formed at the top of the producer. A pair of collars 47 prevents vertical displacement of the screw 46. The end of the lever 44 opposite the pipes 41 and the spreader 40 is provided with a counterweight 48 to balance the weight of the pipes and spreader. The upper end of the screw 46 carries a horizontal wheel 49 provided with radial teeth upon its upper surface. The rod 32 is extended and carries a pin 50 which engages a slot 51 in the free end of a lever 52, the opposite end of this lever 52 being supported by a fixed pivot 53. An arm 54 pivoted to the lever 52 and guided by an extension 55 of a support 56 carries a pawl 57 which engages the radial teeth on the wheel 49. The support 56 also serves to carry the pivots 45 and 53 and is extended to form bearings 58 to guide the upper ends of the pipes 41.

As fuel is added to the gas producer during its normal operation, the thickness of the fuel bed slowly and gradually increases and the surface of the fuel bed therefore gradually rises. It is desirable, of course, that the fuel spreader 40 maintain the same relative vertical position with relation to

the upper surface of the fuel and, in order to accomplish this result, the spreader must rise with the surface of the fuel. As the rod 32 moves back and forth while the ram 14 is feeding coal out of the hopper 12, the screw 46 is given a slow intermittent rotation so as to draw the adjacent end of the lever 44 downwardly and thus raise the spreader 40. If it is found that the spreader 40 has risen either faster or slower than the surface of the fuel, the rate at which the spreader rises may be adjusted to correspond to that at which the surface of the fuel rises by adjusting the effective length 15 of the lever 52. In order that this may be done, the pivoted end of the lever 52 is provided with a series of holes, any one of which may be placed over the pivot 53. The pawl 57 is pivoted so that it may be 20 raised out of contact with the wheel 49 and thus stop the upward movement of the spreader 40, if desired, at any time. In order to obtain an initial adjustment of the spreader 40 to bring it in contact with the 25 surface of the fuel bed, the pawl 57 is raised, and the screw 46 is turned by hand until the desired position of the spreader is secured. If the stop 33 is adjusted toward the ram 14 so as to increase the stroke of the ram and 30 thus increase the rate at which the fuel is fed to the producer, the stroke of the pawl 57 will obviously be also increased so that the fuel spreader will rise more rapidly, a result which is desirable inasmuch as an 35 increase in the rate at which the fuel is fed to the producer will cause a corresponding increase in the rate at which the surface of the fuel will rise within the producer. It is likewise obvious, of course, that if the 40 stop 33 is adjusted to decrease the rate at which the fuel is fed to the producer, it will also at the same time decrease the rate at which the fuel spreader 40 will rise. The stop 33, therefore, serves as a single means 45 for simultaneously adjusting the rate at which the fuel is fed to the producer and the rate at which the fuel spreader rises.

The capacity of the pocket 19 is such that the quantity of fuel fed into it by the ram 50 14 during each of its cycles is not sufficient to fill the pocket, thus permitting the pocket to move its charge of fuel away from beneath the discharge opening of the secondary hopper 17 without the necessity of 55 shearing off lumps of fuel between the upper edge of the pocket and the lower edge of the discharge opening of the hopper. In the retracted position of the ram 14, illustrated in Fig. 2, fuel from the hopper 12 60 drops down on the shelf 13, said shelf being of sufficient length beyond the opening 16 of the hopper to support a definite and predetermined amount of fuel in front of the said ram as determined by the height of the 65 opening 16 above the shelf 13, and by the

angle of repose of such fuel. Each forward movement of the ram 14, therefore, causes a charge of fuel of constant and predetermined amount to drop into the pocket 19, as determined by the adjustment of the stop 70 33, the position of which governs the distance through which the ram is retracted and, consequently, the amount of fuel which drops down in front of the ram to form each charge. 75

It is to be noted, that the adaptation of a feeding mechanism of the character described above, to a gas producer, demands the sealing of the producer chamber against the escape of gas in all positions assumed 80 by the movable pocket member 18. When said pocket member is being charged, the escape of gas is prevented by the shelf 36; when the pocket member is discharging into the producer, the escape of gas is prevented 85 by the co-operation of the shelf 36 with the bottom of shelf 13, the two said parts forming a seal, as shown in Fig. 2. It is particularly to be noted that this seal, formed by the movement of the pocket member which 90 brings shelf 36 beneath shelf 13, is entirely above the level of the fuel which has been segregated in pocket 19 so that no necessity arises for the edge of shelf 13 to shear through the mass of fuel, as would be the 95 case if the pocket 19 were entirely filled. /

I claim—

1. In a fuel feeder for a gas producer, a movable member adapted in one position to receive a charge of fuel, and in another position to discharge said fuel into the producer chamber, means for forming a seal against the escape of gas from said producer chamber when said member is in discharging position, and means for maintaining 100 the level of the fuel charge in said member below the plane of said seal.

2. In a fuel feeder for a gas producer, a reciprocating member adapted in one position to receive a charge of fuel, and in another position to discharge said fuel into the producer chamber, said member having 110 means for forming a seal against the escape of gas from the producer chamber when in discharging position, the plane of said seal 115 being above the level of the charge of fuel in said member.

3. In a fuel feeder for gas producers, a member having a fuel receiving pocket, means for moving said member to bring 120 said pocket into discharging position with respect to the chamber of the producer, means movable with said member to seal the top edge of said pocket against the escape of gas, and means for segregating a 125 charge in said pocket of less volume than the capacity of said pocket.

4. In a fuel feeder for gas producers, a member having a pocket through which fuel may slide by gravity, means for recip- 130

- roating the pocket member, there being a charging opening at one end of the path of the upper end of the pocket and a discharging opening at the other end of the path of the lower end of the pocket, and means for feeding a quantity of fuel insufficient to fill the pocket through the charging opening during each cycle of movement of the pocket member.
10. A gas producer including a chute for conducting fuel into the producer, and vanes within the chute to spread the fuel as it passes through the chute, one of the vanes being angularly adjustable to vary its effect in spreading the fuel.
15. A gas producer including a rotatable section, means for rotating said section, means for feeding fuel to the producer, and projections on said section for operating said feeding means, said projections being removable to vary the rate at which the fuel is fed.
20. A gas producer including means for feeding fuel to the producer, means for spreading the fuel within the producer, and means for simultaneously operating said feeding means and raising said spreading means.
25. A gas producer including means for feeding fuel to the producer, means for spreading the fuel within the producer, and means for simultaneously operating said feeding means and raising said spreading means, the latter means being adjustable to increase the rate at which the fuel is fed to the producer and to decrease the rate at which the spreading means is raised or to decrease the rate at which the fuel is fed to the producer and increase the rate at which the spreading means is raised.
30. In a gas producer, a fuel feeding mechanism, means for spreading the fuel within the producer, means operatively connecting said feeding mechanism with said spreading means to raise the spreading means as fuel is added to the producer, and adjustable means for varying the rate at which the spreading means is raised.
35. In a fuel feeder for gas producers, a member having a pocket, means for feeding a predetermined charge of fuel, less than the capacity of said pocket, to said pocket at predetermined intervals, and means for discharging said pocket between said intervals.
40. In a fuel feeder for gas producers, a member having a pocket, means for automatically feeding a measured charge of fuel, less than the capacity of said pocket, to said pocket, automatic means for discharging said fuel from said pocket into the combustion chamber of the gas producer, and means for sealing said chamber against the flow of gas through said pocket.
45. In a fuel feeder for gas producers, a member having a pocket, automatic means for feeding separate charges of fuel to said pocket, each charge being less than the capacity of said pocket, means acting alternately with said automatic means for discharging the contents of said pocket into the combustion chamber of the gas producer, and means for sealing said chamber against the flow of gas through said fuel feeder.
50. In a fuel feeder for gas producers, a member having a pocket, automatic means for alternately feeding a charge of fuel to said pocket and discharging said charge of fuel from said pocket into the combustion chamber of the producer, each charge of fuel being less than the capacity of said pocket, and means for preventing the flow of gas from said chamber through the fuel feeder.
55. In a fuel feeder for gas producers, a member having a pocket, means for segregating charges of coal of less volume than said pocket, means for feeding said charges at intervals to said pocket, and means for discharging said pocket into the gas producer between said intervals.
60. Dated this seventh day of May 1914.
